J. A. DEWEY,
FOLDING BED,
APPLICATION FILED JAN. 25, 1915.

1,229,242.

Fig. 1

UNITED STATES PATENT OFFICE.

JOSIAH A. DEWEY, OF SAN FRANCISCO, CALIFORNIA, ASSIGNOR TO DEWEY DAVENPORT COMPANY, OF SAN FRANCISCO, CALIFORNIA, A CORPORATION OF CALIFORNIA.

FOLDING BED.

1,229,242.

Specification of Letters Patent. Patented June 12, 1917.

Application filed January 25, 1915. Serial No. 4,190.

To all whom it may concern:

Be it known that I, JOSIAH A. DEWEY, a citizen of the United States, and a resident of the city and county of San Francisco, State of California, have invented a certain new and useful Folding Bed, of which the following is a specification.

The invention relates to that type of folding bed generally known as the davenport or sofa bed.

An object of the invention is to provide an easily operated folding bed.

Another object of the invention is to provide a folding bed of simple and sturdy construction and which possesses a high degree of comfort when used either as a sofa or a bed.

A further object of the invention is to provide a folding bed in which the mattress frames or supports are independently movable in one position and conjointly movable in another position.

The invention possesses other advantageous features, some of which, with the foregoing, will be set forth at length in the following description where I shall outline in full that form of the invention which I have selected for illustration in the drawings accompanying and forming part of the present specification. In said drawings, I have shown one specific form of my generic invention, but it is to be understood that I do not limit myself to such form because my invention may be embodied in a multiplicity of forms, each being a species of my said invention. It is also to be understood that by the claims succeeding the description of my invention, I desire to cover the invention in whatever form it may be embodied.

Referring to said drawings:

Figure 1 is a cross section of the bed of my invention in the folded position.

Fig. 2 is a similar view showing the bed partly unfolded, the bed springs and upper holstery being removed. Fig. 3 is a similar view showing the bed in the unfolded or extended position.

Fig. 4 is a top or plan view of one side of the structure in the extended position.

Fig. 5 is a longitudinal vertical section of one end of the structure showing the locking means for the lower bed frame.

Fig. 6 is a cross section of a portion of the bed, showing a detail of construction.

In the drawings, the invention is embodied in a box couch, but it is evident that the inclosing frame may be made in the davenport style or otherwise. In its present embodiment, the invention comprises a stationary structure having a back 2, sides 3 and front board 4. Arranged in the structure is a lower bed frame comprising the rectangular frame 5 upon which the coiled springs 6 are mounted, the upper ends of which springs are joined by a suitable flexible structure 7 upon which the upholstered mattress rests. The lower bed frame is normally disposed at the bottom of the structure. Secured to the sides 3 at opposite ends of the structure are guides 8—9 preferably vertically arranged, which may be formed of channel irons, the channels being closed at their lower ends. Secured to the frame 5 and engaging in said guides are slides 12—13, which preferably extend above the frame 5. The slides preferably consist of angle irons having one leg bolted to the frame 5 and the other lying in the groove of the channel and when the frame is in the depressed position the slides engage the closed lower end of the channels, supporting the lower frame. The slides are of such length that they will not bind in the guides.

Arranged in superposed relation with respect to the lower bed frame, when the bed is folded, is the upper bed frame, composed of the rectangular frame 14 upon which are mounted the coil springs 15, which are connected together at their free ends by a suitable flexible structure 16. When the bed is folded, the upper bed frame is inverted, and in the present structure, sufficient space is left between the flexible structures 7 and 16 of the spring mattress to accommodate a double or folded upholstered mattress. On the upper side of frame 14 is arranged a suitably upholstered seat 17.

The upper frame 14 is pivoted adjacent its forward side by pivots 18 arranged in or secured to the sides 3. The pivots 18 are preferably stationary and are engaged by plates 19 secured to the opposite ends of the frame 14 at the forward side. The position of the pivots 18 and the height of the back

2 are related so that when the upper frame is folded it lies in the horizontal position. The upper frame is movable from its horizontal folded position through an arc of 5 180 degrees to its extended horizontal position.

Means are provided for allowing the upper frame 14 to rotate independently of the lower frame 5, through a given arc from its 10 horizontal folded position and for causing the further unfolding movement of the upper frame to be accompanied by a raising movement of the lower frame, so that the two frames are moved into alignment as they 15 reach their unfolded or extended position. By means of this partly independent and partly-conjoint movement of the bed frames, the bed is easily unfolded, since it is only necessary to raise the upper frame. The 20 conjoint movement does not begin until after the upper frame has reached its vertical position, and the downward movement of the frame is accompanied by an upward movement of the lower frame. The connections 25 between the frames are such that the weight of the descending frame is counterbalanced by the weight of the ascending frame, making the bed very easy of operation.

Attached to the lower frame 5 at the centers of the opposite ends are links 21 which are connected at their free ends to links 22 pivoted to the plates 19, by pivots 23 spaced from the pivots 18. The pivots 30 23 and 18 on each plate are so arranged with relation to each other that the link 22 contacts with the pivot 18 at a point intermediate between the ends of the link when the upper frame 14 reaches or passes its 35 vertical position in its unfolding movement. The link 22 is thereby converted into a lever with its fulcrum at the pivot 18 and the further downward movement of frame 14 causes the lever 22 to move the lower frame 40 upwardly in its guides 8-9, to a position of alignment with the unfolded upper frame. Legs 24 pivoted to the upper frame swing 45 downward into contact with the floor and support the outer end of the unfolded upper frame.

Means are provided for locking the lower frame in its elevated position. Arranged on the sides 3 above the guides 8-9 are spring pressed latches 25-26, the bolts 27 50 of which lie in the planes of the guides 8-9. Each slide 12-13 is provided with a seat 28, which when the lower frame is elevated, is engaged by said bolts, holding the frame in its raised position. Connected 55 to the bolts is a cord 29 which extends along the outer side of the lower frame when the bed is unfolded and by pulling on this cord, the latches are released and the bed may be folded.

Means are also provided for assisting in

the raising movement of the upper frame from the unfolded position. Secured to and surrounding the pivot 18, is a stiff spring 31, the free end of which presses against the under side of the frame, tending to raise it. 70

I claim:

1. In furniture of the class described, two superposed bed frames, the upper frame being pivotally supported adjacent its forward side and being movable about said pivot 75 through a predetermined arc independent of the lower frame, and means including a link pivoted to said upper frame at a point outside the pivotal axis of said frame and operative by the further movement of the upper frame for moving the lower frame.

2. In furniture of the class described, a lower bed frame, an upper bed frame arranged in superposed relation therewith, pivots supporting the upper frame at its forward side, a link pivotally connected at each end of the lower frame at the center, and a link connecting each of said center links with the upper frame, said last named links being convertible into supporting levers for 85 said lower frame as the upper bed frame is moved about its pivot.

3. In furniture of the class described, a lower bed frame adapted to be raised, an upper bed frame arranged in superposed relation with said lower frame adapted to be rotated about a horizontal axis, and links connected to said lower bed frame and pivoted to said upper bed frame at a point outside 95 said axis whereby the initial movement of the upper frame about said axis is independent of the lower frame and the further movement of the upper frame converts said links into levers which operate to raise the lower frame. 100

4. In furniture of the class described, a stationary structure, guides arranged on said structure, a lower bed frame movable in said guides, an upper bed frame arranged above said lower frame and pivoted to said structure, and means connecting said upper and lower bed frames whereby the downward movement only of the upper frame causes an upward movement of the lower frame and the upward movement only of the upper 115 frame causes a downward movement of the lower frame.

5. In furniture of the class described, a stationary structure, guides arranged on said structure, a lower bed frame movable in said 120 guides, an upper bed frame arranged above said lower bed frame and pivoted to said structure, links connected to said lower frame, and links connecting said first named links with the upper bed frame, said 125 second links being arranged to engage the pivots of the upper frame after the upper frame has been moved past the vertical position in its unfolding movement.

6. In furniture of the class described, an 130

upwardly movable lower bed frame, a pivoted upper bed frame arranged to be moved through a vertical arc from the folded to the unfolded position, means connecting said bed frames operative by the descending movement only of said upper frame to raise the lower frame and by the descending movement of the lower frame to raise the upper frame, and means for locking the lower frame in its raised position.

7. In furniture of the class described, a stationary structure, an upwardly movable lower bed frame arranged in said structure, a pivoted upper bed frame arranged to be moved through a vertical arc from a folded to an unfolded position, links connecting said frames operative by the downward movement of the upper frame to raise the lower frame and by the downward movement of the lower frame to raise the upper frame, means on said stationary structure for locking the lower frame in its raised position, and means for releasing said locking means.

8. In furniture of the class described, a stationary structure, guides secured to said structure, a lower bed frame arranged in said structure, slides on said frame engaging in said guides, an upper bed frame pivoted to said structure adjacent its forward side, links connecting said lower frame with the upper frame at points spaced from said pivots, the pivotal point of the link and the pivot of the upper frame being so arranged that the links engage said pivots during the rotation of the upper frame, the further movement of the upper frame serving to raise the lower frame, and latches adapted to engage said slides and lock the lower frame in the raised position.

In testimony whereof, I have hereunto set my hand at San Francisco, California, this 19th day of January, 1915.

JOSIAH A. DEWEY.

In presence of—
H. G. PROST,
NETTIE THREW.
